United States Patent Office

Des. 190,383
Patented May 23, 1961

190,383

MEASURING SCOOP

Arnold E. Hanson, 2940 Lorain Road, San Marino, Calif.

Filed Sept. 23, 1960, Ser. No. 62,253

Term of patent 14 years

(Cl. D44—29)

Fig. 1

Fig. 2

Fig. 3

Fig. 4

Figure 1 is a top plan view of a measuring scoop showing my new design;

Figure 2 is a front elevation thereof;

Figure 3 is an end elevation thereof; and

Figure 4 is an opposite end elevation thereof.

I claim:

The ornamental design for a measuring scoop, substantially as shown.
